CLAIM

The ornamental design for a microphone windscreen, as shown and described.

DESCRIPTION

FIG. 1 is a perspective view of a microphone windscreen showing the new design;

FIG. 2 is a front elevational view of the microphone windscreen, a rear elevational view of the microphone windscreen being mirror symmetrical to the front elevational view;

FIG. 3 is a top plan view of the microphone windscreen;

FIG. 4 is a bottom plan view of the microphone windscreen;

FIG. 5 is a right side elevational view of the microphone windscreen, a left side elevational view of the microphone windscreen being mirror symmetrical to the right side elevational view; and,

FIG. 6 is a cross-sectional view of the microphone windscreen taken in the direction of line 6-6 of FIG. 2.

The broken lines in the drawings depict portions of the microphone windscreen that form no part of the claimed design.

1 Claim, 6 Drawing Sheets
